United States Patent Office

Des. 222,113
Patented Sept. 28, 1971

222,113

TOY ORGAN

Stanley G. Novaco, Nutley, N.J., assignor to Proll
Products Co., Newark, N.J.

Filed Aug. 25, 1970, Ser. No. 24,684

Term of patent 14 years

Int. Cl. D17—01

U.S. Cl. D56—2

FIG. 1.

FIG. 2.

FIG. 3.

FIG. 4.

FIG. 1 is a front, top and right side perspective view of a toy organ, showing my new design;

FIG. 2 is a rear elevational view;

FIG. 3 is a right side elevational view, the left side being substantially a mirror image thereof; and

FIG. 4 is a bottom plan view thereof.

I claim:

The ornamental design for toy organ, as shown.
